Primary Examiner — Bridget L Eland*(74) Attorney, Agent, or Firm* — Nir Lifshitz**CLAIM**

The ornamental design for a steerable catheter handle, as shown and described.

DESCRIPTION

FIG. 1 is a top front perspective view of an steerable catheter handle, showing our new design;

FIG. 2 is a top rear perspective view of the steerable catheter handle of FIG. 1;

FIG. 3 is a right side elevational view of the steerable catheter handle of FIG. 1;

FIG. 4 is a left side elevational view of the steerable catheter handle of FIG. 1;

FIG. 5 is a top plan view of the steerable catheter handle of FIG. 1;

FIG. 6 is a bottom plan view of the steerable catheter handle of FIG. 1;

FIG. 7 is a front elevational view of the steerable catheter handle of FIG. 1; and,

FIG. 8 is a rear elevational view of the steerable catheter handle of FIG. 1.

The broken lines immediately adjacent the shaded areas represent the bounds of the claimed design while all other broken lines are directed to environment and are for illustrative purposes only; the broken lines form no part of the claimed design.
